UNITED STATES PATENT OFFICE.

CHRISTIAN TRAUGOTT GOLDBERG, OF NEUKIRCHEN, GERMANY.

FANCY-ROLLER FOR CARDING-ENGINES.

SPECIFICATION forming part of Letters Patent No. 635,927, dated October 31, 1899.

Application filed December 3, 1898. Serial No. 698,160. (No model.)

To all whom it may concern:

Be it known that I, CHRISTIAN TRAUGOTT GOLDBERG, spinner-master, a subject of the King of Saxony, residing at Neukirchen, in the Kingdom of Saxony, German Empire, have invented new and useful Improvements in Fancy-Rollers for Carding-Engines, of which the following is a specification.

In carding-machines in order to lift the fibers which enter between the teeth of the drum in passing the workers there was used a fly or fancy roller which had to bring the fibers to the point of the cards, so as to enable the doffer to grasp the fibers. For this purpose the fly or fancy roller was provided with cards in the kind of a brush which by the great elasticity and the particular position of the teeth were enabled to catch in the teeth of the drum and to lift the fibers.

20 The fly or fancy roller commonly consists in a wooden roller with several carding-sheets having long and elastic teeth set at a certain angle, by which position of the teeth and the very rapid revolution of the roller the lifting of the fibers is attained. By the working of this fly or fancy roller the flying out and about of the fibers cannot at all be avoided in consequence of the great movement of air at the circumference of the roller resulting

25 from the rapid revolution of the latter. The light fibers thus sucked and spread about deposit upon the fleece and are the cause of ununiformity. The present invention has for its object to overcome this deficiency.

30 Figure 1 shows the parts of a carding-engine in section. Fig. 2 is an elevation of the parts shown in Fig. 1. Fig. 3 is a sectional view of one of the rollers of the fly or fancy rollers.

35 The carding-teeth are set in an endless band of leather, cloth, or other suitable material *a*, which is carried on by two rollers *b* *c* of the whole width of the carding-engine. The roller *b*, of larger diameter than roller *c*, receives its movement from the drum *d* by

means of a pulley *e*, carried on the axis of the roller *b*, while roller *c*, of smaller diameter, is rotated by the friction of the endless band *a* upon its circumference and is adjustably supported in bearings *f* for 50 the purpose of regulating the tension of the endless band *a*. The latter moves in the direction of the arrow, and the carding-teeth travel in a straight line from the point where they enter the drum to the point where they 55 leave the drum *d*. For the purpose of attaining a safe guide of the carding-band upon its rollers the latter are provided with recesses *g* *g'*, and upon the endless band *a* are riveted straps *h*, which enter the recesses. 60 A casing *i*, surrounding the two rollers *b* *c*, serves as protector for the cards of the fly or fancy roller. By this arrangement the carding-teeth of the fancy-roller do not leave the drum *d* in a circular line, as hitherto, but in 65 a line which is directed tangential to the circumference of the drum *d*. Moreover, in consequence of this arrangement a much greater number of carding-teeth are acting with the teeth of the drum *d*, by which the employment of a less number of revolutions of the fly or fancy roller is afforded, and a destructive air circulation by which the light fibers could be blown about is avoided.

Having now described and ascertained my 70 said invention and in what manner it is to be performed, I declare that what I claim is—

In a carding-engine, a fly or fancy roller comprising a pair of parallel rollers journaled in proximity to the main cylinder, an endless 80 carding-sheet carried by said rollers and running with its surface tangential to said main cylinder, and means for driving one of said rollers, substantially as described.

In witness whereof I have hereunto set my 85 hand in presence of two witnesses.

CHRISTIAN TRAUGOTT GOLDBERG.
